UNITED STATES PATENT OFFICE.

ELMORE ROY BUTLER AND FREDERICK ALEXANDER STOKES, OF TORONTO, ONTARIO,
CANADA.

CONTRIBUTION OR COLLECTION BOX.

1,174,672.

Specification of Letters Patent.

Patented Mar. 7, 1916.

Application filed March 2, 1915. Serial No. 11,614.

To all whom it may concern:

Be it known that we, ELMORE ROY BUTLER and FREDERICK ALEXANDER STOKES, both subjects of the King of Great Britain, 5 and both residing in the city of Toronto, county of York, Province of Ontario, Canada, have invented new and useful Improvements in Contribution or Collection Boxes, of which the following is a specification.

Our invention relates to improvements in collection or contribution boxes and relates more particularly to the production of a box of this class to be used for securing public 15 subscriptions to charitable institutions, and the principal object of our invention is to provide our box with means whereby each time a coin is inserted in the box a different text will be disclosed, thus largely contributing to the maintenance of 20 the public interest in the institutions using the box, and the construction of our invention will be hereinafter particularly set forth and what we claim as new will be pointed 25 out in the claims of this specification.

Figure 1 is a perspective view of our box and Fig. 2 is a perspective view of the coin receptacle, and portion of the upper part of the box, in tilted position, to show certain 30 interior parts. Figs. 3 and 4 are views of the rear side of the box, with the cover opened and partly shown in section, certain parts being broken away in Fig. 4 to facilitate illustration of construction. Fig. 5 is 35 a perspective view of the pawl and the supporting plate therefor. Fig. 6 is a longitudinal section on the line 6—6 Fig. 1, Fig. 7 is a vertical cross section on the line 7—7 Fig. 3, and Fig. 8 is a horizontal cross section on the line 8—8 Fig. 3 through the lower portion of the casing and the cover 40 therefor.

In the drawings like characters of reference indicate corresponding parts in each 45 figure.

Our collection or contribution box comprises a coin receptacle A of any suitable construction, the same being preferably provided with a transparent face B, preferably 50 made of glass held in position by any suitable means.

C is a closure member suitably hinged as at D to one end of the box to permit the contents thereof to be periodically removed.

55 E is a lug carried by the box and project-

ing through the top of the closure member C. By means of this lug any suitable lock or fastening means may be employed to lock the closure member closed.

The construction just described is of course well known.

Carried by the rear wall F, of the coin receptacle A are side walls H. The head I of this casing is preferably shaped as shown, and housed therewithin is a disk J and means for operating and supporting the same hereinafter particularly set forth. Hinged as at 2 to the rear wall F is the cover 3 which is of the same shape as the said casing and designed to close the same. 70 The flanges 4 of the cover 3 are designed to fit within the side walls H of the said casing, as will be understood, thus protecting the disk J and their parts. Formed in the face wall G of the head I is an opening 75 6 preferably covered by some suitable transparent material such as glass which is held in position after any suitable manner. 7 is a stud preferably positioned centrally in respect of the face wall G, and carried thereby and positioned within said head. Mounted on said stud is a sleeve 8 to which is suitably secured the ratchet 9. The disk J is also mounted on the sleeve 8, and may be suitably secured thereto by any suitable 80 means. Since the disk J is designed to carry a number of different texts or mottoes for successive exposure through the opening 6, we prefer to construct this disk of card board so that said texts or mottoes may be 90 printed thereon. Using the material mentioned enables us to very considerably reduce cost of manufacture, and as the cover 3 co-acting with the casing before mentioned, will house the members within said 95 housing, it will be understood that the same will be protected from the weather. Since we prefer to make the disk J of card board, we mount on the sleeve 8 a fastening disk *j* which is positioned intermediate the disk J 100 and the ratchet 9. By cementing or otherwise securing the said disks together, and the disk *j* to the ratchet 9, we couple the disk J to the sleeve 8. Also mounted on the sleeve 8 is a disk 10 preferably made of 105 metal which gives good support to the disk J to keep the same from buckling.

11 is a nut screwing on the threaded end of the sleeve 8 and clamping the parts before mentioned together, and 12 is a nut 110

screwing on the threaded end of the stud 7 to retain the parts before set forth on said stud.

In the top 13 of the coin receptacle A is formed any suitable coin slot 14.

15 are a pair of guard plates suitably secured to the underside of the top 13 and depending therebelow. The said guard plates are spaced apart to permit the coin 10 to be passed therebetween.

When the coin is inserted through the slot 14, it comes in contact with the coin plate or lever 16 which plate or lever is secured to the rod 17 journaled in suitable brackets 18 carried by the top 13 and depending therebelow. 19 is an arm forming part of the rod 17, which projects through the face wall G, and this arm is positioned behind said face wall and is provided with 20 a bent end 20 which normally is positioned below the heel 21 of the supporting plate 22 which has vertical reciprocating movement between the guides 23 carried by the rear side of the face wall G. As the arm 19

25 projects beyond the rod 17 in the direction opposite to the coin plate or lever 16, (see dotted lines Fig. 6) it will be understood that when said plate or lever 16 is depressed, said arm 19 is elevated, thus bringing the 30 bent end 20 thereof in contact with the heel 21, and so raising upward the plate 22. 24 is a pawl pivoted by the pin 25 to the plate 22, and in its normal position the lug 26 secured to or forming a part of said pawl 35 rests in contact with one of the teeth of the ratchet 9, and consequently during the upward movement of the plate 22, said pawl is moved for the distance of one tooth. The movement of this ratchet of course moves 40 the disk J thus exposing through the opening 6 a motto or text different to that previously exposed through said opening. So soon as the coin leaves the plate or lever 16, the plate 22, together with the pawl 24, by

45 reason of their weight, drop back to normal position, thus returning the plate or lever 16 and arm 19 to normal position. In order to permit of the return to normal position of the pawl 24, the lug 26 thereof is held 50 by the spring 27 (the lower end of which is secured at 28 to the plate 22) in contact with the ratchet 9, so that this said lug will ride over the back *a* of each of the teeth of said ratchet and be moved into proper position at the right time.

In order to limit the movement of the pawl 24 toward the ratchet 9, any suitable means may be employed. Our preferred construction for this purpose consists in 60 forming a notch *b* in the upper end of the plate 22 and bending the end *c* of the pawl 24 inwardly so that the same will abut against the wall *d* of said notch and so limit the described movement of said pawl.

65 In order to prevent any overthrow move-

ment of the disk J, we provide a shoe *e* coupled by a suitable spring *f* to the rear side of the face wall G. The shoe *e* is spring held against the ratchet 9, and it performs the function of a brake for the purpose set forth. It will of course be understood that each time the ratchet 9 is moved the shoe *e* will yield to permit of this movement.

The guard plates 15, it will be understood, 75 prevent the coin passing through the coin slot 14 from slipping sidewise and so avoid depressing the coin plate or lever 16 the desired distance.

If desired, surrounding the sides and bottom of the lower portion *o* of the face wall G, we may provide the retaining flanges *l* and *m* so as to form a pocket, so to speak, in which any suitable card *n*, shown by dotted lines, may be inserted, the said card 80 to contain illustrated or printed matter as 85 may be desired, to further increase the power of the box to attract attention.

What we claim as our invention is:

1. In a contribution or collection box the 90 combination with the coin receptacle thereof provided with a coin slot, of a casing carried by said coin receptacle and provided in the face wall of its upper portion with an opening; a stud carried by said face wall 95 and positioned within said casing; a sleeve mounted on said stud; a disk mounted on said sleeve, and moving therewith; said disk being provided with a number of different texts or mottoes; a ratchet mounted on said sleeve and secured thereto; means whereby said sleeve is retained on said stud, a vertically disposed plate mounted within said casing; suitable means for guiding said plate; a pawl pivoted to said plate and designed to co-act with the teeth of said ratchet; a spring for yieldingly maintaining said pawl in normal position; means for limiting the movement of said pawl toward said ratchet wheel, and means whereby when 100 a coin is inserted in said coin slot, said plate will be elevated so that the pawl carried thereby will move said ratchet a distance of 105 one tooth, for the purpose specified.

2. In a contribution or collection box the 115 combination with the coin receptacle thereof provided with a coin slot, of a casing carried by said coin receptacle and provided in the face wall of its upper portion with an opening; a stud carried by said face wall 120 and positioned within said casing; a sleeve mounted on said stud; a disk mounted on said sleeve, and moving therewith; said disk being provided with a number of different texts or mottoes; a ratchet mounted on said sleeve and secured thereto; means whereby said sleeve is retained on said stud, a vertically disposed plate mounted within said casing; suitable means for guiding said plate; a pawl pivoted to said plate and de- 125 130

signed to co-act with the teeth of said ratchet; a spring for yieldingly maintaining said pawl in normal position; means for limiting the movement of said pawl toward 5 said ratchet wheel; means whereby when a coin is inserted in said coin slot, said plate will be elevated so that the pawl carried thereby will move said ratchet a distance of one tooth, and means co-acting with said 10 ratchet to prevent any undue movement thereof for the purpose specified.

3. In a contribution or collection box the combination with a coin receptacle thereof provided with a coin slot, of a casing carried 15 by said coin receptacle and provided in the face wall of its upper portion with an opening; a stud carried by said face wall and positioned within said casing; a sleeve mounted on said stud; a disk mounted on said 20 sleeve, and moving therewith; said disk being provided with a number of different texts or mottoes; a ratchet mounted on said sleeve and secured thereto; means whereby said sleeve is retained on said stud, a vertically disposed plate mounted within said 25 casing; suitable means for guiding said plate; a pawl pivoted to said plate and provided with a lug which is designed to co-act with the teeth of said ratchet; a spring for 30 yieldingly maintaining said pawl in normal position; means for limiting the movement of said pawl toward said ratchet wheel comprising a toe at the upper end of said pawl bent to abut against the upper end of said 35 plate, and means whereby when a coin is inserted in said coin slot, said plate will be elevated so that the pawl carried thereby will move said ratchet a distance of one tooth, for the purpose specified.

4. In a contribution or collection box the 40 combination with a coin receptacle thereof provided with a coin slot, of a casing carried by said coin receptacle and provided in the face wall of its upper portion with an opening; a stud carried by said face wall and positioned within said casing; a sleeve mounted on said stud; a disk mounted on said 45 sleeve, and moving therewith; said disk being provided with a number of different texts or mottoes; a ratchet mounted on said 50 sleeve and secured thereto; means whereby said sleeve is retained on said stud; reciprocating means mounted within said casing to co-act with said ratchet to turn it one tooth at a time; a coin lever positioned with 55 its end extending underneath said coin slot in said coin receptacle; a rod journaled in said coin receptacle and to which said coin lever is secured, one portion of said rod being formed into an arm to extend in a direction therefrom opposite to the direction of extension of said coin plate, the said coin plate designed to be moved downwardly when a coin is inserted in said coin slot to move said arm upwardly so as to operate 60 said vertically reciprocating means, and means carried by said coin receptacle and adjacent said coin slot to prevent the inserted coin from passing into said coin receptacle without depressing said coin plate, 65 as set forth.

In testimony whereof we have affixed our signatures in presence of two witnesses.

ELMORE ROY BUTLER.

FREDERICK ALEXANDER STOKES.
